UNITED STATES PATENT OFFICE.

ERZA A. NEWHALL, OF PHILADELPHIA, PENNSYLVANIA, ASSIGNEE OF ONE-FIFTH TO
STEDMAN BENT, OF PHILADELPHIA, PENNSYLVANIA.

VACUUM EVAPORATING APPARATUS.

1,149,939.

Specification of Letters Patent. Patented Aug. 10, 1915.

Application filed May 7, 1914. Serial No. 387,063.

To all whom it may concern:

Be it known that I, EZRA A. NEWHALL, a citizen of the United States, residing in Philadelphia, Pennsylvania, have invented certain Improvements in Vacuum Evaporating apparatus, of which the following is a specification.

This invention has to do with auxiliary apparatus for use in connection with evaporating systems and one object thereof is to increase the efficiency of such systems, particularly those of the multiple effect type, the invention contemplating the provision of a relatively simple and compact combination of parts for removing air and other comparatively uncondensable gases from the steam boxes of the effects or evaporators with a view to relieving the main air pump of this work.

It is also desired to provide apparatus whereby flooding of the steam boxes with water as well as free passage of steam from one of said boxes to one or more of the others or to a suction device will be automatically prevented by means which shall include a construction for utilizing a portion of the heat in the water of condensation.

Another object of the invention is the provision of the above apparatus with such attachments as will cause it to continue its automatic operation without interruption; the device for removing air from the steam boxes including means for utilizing the heat still contained in the steam used for operation.

These objects and other advantageous ends I secure as hereinafter set forth, reference being had to the accompanying drawings, in which,

Figure 1 is a front elevation, to some extent diagrammatic, illustrating a multiple effect evaporating system equipped with my invention; Fig. 2 is a plan of the apparatus shown in Fig. 1, and Figs. 3 and 4 are elevations, of which the latter is partly in section, illustrating one of the features of the invention.

In Figs. 1 and 2 of the above drawings 1, 2, and 3 represent the effects of a multiple effect evaporating system, the casing of the first effect being connected to deliver steam or water vapor to the steam-box 4 of the effect 2 through a pipe 5, and the casing of this latter effect being connected through a

pipe 6 to deliver vapor to the steam box 7 of the effect 3.

Steam for heating the first effect is delivered to the steam box 8 thereof through a pipe 9 and the casing of the last effect 3 is connected through a pipe 10 with the suction chamber of cylinder 11 of a main air pump 12.

Liquor to be concentrated is delivered to the casing of the first effect 1 through an inlet pipe 13 and said casing is connected to deliver partly concentrated liquor to the casing 2 through a valved pipe 14. Similarly, the casing of the last effect 3 is connected to receive, through a valved pipe 15, liquor from the casing of the last previous effect and is provided with an outlet pipe 16 for the completely concentrated liquor.

The steam boxes 8, 4, and 7, of the three effects all have their top portions connected to an air ejection pipe 17 whose outlet end is connected to an air educting device 18 consisting of an ejector supplied with steam from a pipe 19. Said ejector discharges into a heater 20 having an inlet 21 and an outlet 22 which may be connected respectively to a source of liquor to be concentrated and to the casing of the first effect 1, in order that the temperature of the liquor may be raised as high as possible before delivery to said effect.

Each of the effects has its steam box downwardly extended as indicated at 23 to provide a collecting box for condensed water and these two boxes of the effects 1 and 2 are connected through a valved pipe 24 while the boxes 2 and 3 are connected through a valved pipe 25. The water box of the last effect 3 is connected through a valved pipe 26 to a pump 27, although, as shown in Fig. 3, it may, under certain conditions, be connected to the suction chamber of the main air pump 12, or as shown in Fig. 4, to the discharge leg 28 of a barometric or other similar condenser 29.

Each of the water boxes of the several effects is entered by a pipe 30 at some point above its bottom at which it is desired that the water level shall normally stand, and each of said pipes 30 in turn is connected to a steam trap 31 whose outlet or discharge pipe 32 is connected into the main pipe for condensed water 24, 25, or 26, as the case may be, at some point beyond its stop valve

33. Moreover, the highest portion of the dome of each steam trap is connected through a pipe 34 with its discharge pipe 32.

With this arrangement of parts the operation of the main air pump 12 creates a relatively high vacuum in the casing of the last effect 3 and when steam is supplied to the pipe 9 the liquor in the several effects is boiled under a pressure which decreases from the first to the last effect in the well known manner.

Even under the best conditions, more or less air and other uncondensable gases ordinarily collect in the steam boxes of the several effects, but by the use of the ejector 18 these may be very effectually removed, the heat of the steam used for this purpose as well as that of the steam and air removed from the effects being utilized in the heater 20 for any purpose, such as raising the temperature of the liquor to be concentrated. This removal of the air from the steam box removes a material portion of the load from the air pump 12, making possible the attainment of a higher vacuum than could ordinarily be secured and, consequently, increasing the efficiency of the system as a whole. This is due to the fact that the pump 12 which is customarily connected to the pipe 17 is not required to remove the air from the several steam boxes, in addition to producing a vacuum and condensing the steam.

If the valves 33 in the water pipes 24, 25, and 26 are at all times fully open, I have found that there will be such a complete removal of the water as will permit blowing through and consequent waste of the steam. On the other hand if these valves are throttled there will be flooding of the water boxes, part of the time at least, so that constant regulation is necessary. With the apparatus shown and described above, I throttle or partly close the valves 33, thus maintaining a body of water in each of the water boxes 23 whose level is determined by the point of entrance of the pipes 30. If, at any time, the water should rise above this level, it would at once be removed by the automatic action of the steam trap 31 connected to said box, and be delivered thereby through the pipe 32 into that portion of the water pipe on the suction side of the valve 33 having free communication with the water box of the next effect.

55 Obviously the vacuum in the pipe 32 is higher than that in the trap attached thereto, so that any air which might accumulate in the dome or top of said trap would be at once removed through the pipe 34.

60 By providing a more or less extended surface of water in the water box attached to or forming part of each steam box, I permit of the liberation therein of a certain amount of the heat carried by said water, and at the same time the trap associated with each box

provides an automatically acting overflow therefor.

The condensed water delivered from the last effect through its trap 31 and discharge pipe 32 is removed either by a special drip pump 27, by the main air pump 12, or by the condenser 29; the connection of said pipe to the water leg of such condenser being made at some point below the level at which water is maintained therein.

75 From the above it will be noted that by means of my apparatus I am enabled to effect material savings which altogether result in a decided increase in the efficiency of the apparatus as a whole, for not only is the air, etc., removed from the several steam boxes in such a manner as to permit of the maintenance of higher vacuums in the system than could otherwise be obtained, but the blowing through of steam from one steam box to that of another effect or from the last steam box to the suction device, is effectually prevented. At the same time the condensed water is caused to give up more of its heat than has ordinarily been obtainable, while flooding of any of the steam boxes is also effectually prevented.

90 I claim:

1. The combination with a multiple effect system of a condensation pipe connecting the several effects; suction producing means; a pipe connecting said means with the steam box of the last effect; a valve in each of said pipes; and steam traps respectively connected to each effect and to the condensation pipe leading therefrom on the suction side of the valve therein.

95 2. The combination in a multiple effect system of a pipe for carrying off the condensed water from one of the effects; a valve in said pipe; with a steam trap connected to the steam box of said effect and discharging into the pipe on the suction side of said valve.

100 3. The combination of an evaporator having a steam box; a pipe connected to a suction device for removing condensed water from said steam box; a valve in said pipe; a steam trap; a pipe connecting said trap with the steam box; and a discharge pipe connecting the steam trap with the condensed water pipe on the suction side of the valve therein.

110 4. The combination of an evaporator having a steam box; a pipe connected to a suction device for removing condensed water from said steam box; a valve in said pipe; a steam trap; a pipe connecting said trap with the steam box; a discharge pipe connecting the steam trap with the condensed water pipe on the suction side of the valve therein; with a pipe connected to the discharge pipe of the steam trap for removing the air from said trap.

115 5. The combination of an evaporator hav-

- ing a steam box; a pipe connected to a suction device for removing condensed water from said steam box; a valve in said pipe; a steam trap; a pipe connecting said trap with the steam box; a discharge pipe connecting the steam trap with the condensed water pipe on the suction side of the valve therein; with means for removing the air from said trap.
- 5 10 6. The combination in a multiple effect system of condensation water pipes connecting the steam boxes; suction means connected to remove the condensed water from the steam box of the last effect; valves in said
- water pipes; a steam trap connected between each steam box and a part of the water pipe leading therefrom on the suction side of the valve therein; and an air removing pipe connecting the top of each steam trap with the discharge pipe thereof.
- 15 20 In testimony whereof, I have signed my name to this specification, in the presence of two subscribing witnesses.
